ATTORNEY

UNITED STATES PATENT OFFICE

HARRY L. EIGENBROT, OF SAN FRANCISCO, CALIFORNIA

SADIRON

Application filed July 2, 1928. Serial No. 290,010.

This invention relates to improvements in electric iron attachments, and has particular reference to an attachment for use with the ordinary clothes-pressing sad iron.

5 The principal object of this invention is to provide a switch positioned upon the sad iron, which switch may be operated either manually or thermostatically.

Another object is to provide a device of this 10 character which is simple in construction and one which may be attached to the ordinary iron without altering the construction of the same.

A further object is to provide a device 15 which is neat in appearance, and economical to manufacture.

Other objects and advantages will be apparent during the course of the following description.

20 In the accompanying drawings forming a part of this specification, and in which like numerals are employed to designate like parts throughout the same,

Figure I is a side elevation of a sad iron 25 having my device applied thereto, and

Figure II is an enlarged detail cross-section of the handle showing the switch mechanism.

I have provided a switch secured to the 30 handle of the sad iron, which switch is operated by the hand of the operator.

In the accompanying drawings forming a part of the specification and wherein for the purpose of illustration is shown a preferred embodiment of my invention, the numeral 5 designates the base or body of the iron proper, which base may be of any convenient form capable of use in smoothing clothes. This base carries an upstanding U-shaped metal support 6, between the ends of which is positioned a handle 7. The usual heating element is designated at 8 and the socket is shown at 9. This socket is of the usual construction, and serves to connect the iron to the source of electrical energy.

The construction thus far is found in all irons and forms no part of my invention.

In accomplishing my object I employ a 50 thermostatic rod 11, one end of which engages the heating element 8 while the op-

posite end is in close proximity to the handle 7. The upper end is provided with an adjustable extension 12, which extension underlies the short arm 13 of a pivoted switch lever 14. This lever is pivoted as at 16 and due 55 to the difference in length between the arm 13 and the lever 14, it is apparent that a very short movement of the thermostatic rod 11 will cause a considerable movement of the lever 14.

The end of the lever 14 is adapted to engage a contact 17 carried upon the end of a tapered lever 18. This operating lever is mounted upon a traveling pin 19 carried in a slot 21 formed in the handle 7.

60 A thumb piece 22 provides a convenient means for moving the sliding pin 19.

A contact 23 serves to conduct electric current from the wire 24, which wire is in turn connected to the socket 9, to the operating 70 lever 18. The switch 14 is connected by a wire 26 to the heating element 8, which heating element is in turn connected to the socket 9 thus completing the electrical circuit.

75 The manner in which my device operates is as follows:—

Assuming that the socket is connected to the source of electrical energy, current will 80 flow from one side of the iron to the heating element, thence through the heating element to the wire 26 to switch 14, through contact 17, operating lever 18, contact 23 to wire 24 and back to the opposite side of the socket 9.

85 When the heat of the iron has reached a pre-determined amount, the rod 11 will expand and will cause the switch 14 to move out of engagement with the end of the lever 18, as shown in dotted lines of Figure II. 90 This will break the circuit, and consequently the iron will cease heating.

Upon a cooling of the iron, the rod 11 will contract and close the switch 14 and heating will occur.

95 When the operator is using the iron, the grasping of the handle will push upwardly upon the lever 18 and hold the same in contact with the switch 14. Therefore, the iron will remain on heat during the ironing oper-

ation, unless the operator wishes to disconnect the electric circuit in which event, the thumb piece 22 is pushed forwardly which will move the tapering lever 18 to the dotted line position of Figure II.

5 It will thus be seen that I have produced an iron having a control mechanism therein which will perform all of the objects herein set forth.

10 It is to be understood that the form of my invention herewith shown and described is to be taken as a preferred example of the same, and that various changes relative to the shape, size, material and arrangement of parts may be resorted to without departing from the spirit of the invention or the scope of the subjoined claim.

15 Having thus described my invention, I claim:—

20 In a device of the type described a heating element positioned therein, and a handle positioned therein, a rod contacting said heating element and having its opposite extremity in close proximity to said handle, a switch 25 lever pivotally mounted in said handle and adapted to be actuated by said rod, an operating lever pivotally mounted in said handle and adapted to contact said switch lever and means for moving said lever into and out of 30 engagement with said switch lever by shifting the pivotal point of said tapering lever.

In testimony whereof I affix my signature.

HARRY L. EIGENBROT.
